SKIN, HIDE AND LEATHER WORKING
MACHINE

Frank Wayland, Camden, N. J.

Application July 31, 1937, Serial No. 156,709

7 Claims. (Cl. 149—20)

This invention relates to machines for putting out, staking, fleshing and unhairing skins, hides and leather and consists in certain improvements upon the machines of this class which are illustrated and described in my U. S. Letters Patent Nos. 1,077,207; 1,090,895; 1,131,756 and 1,204,914.

In the accompanying drawings which illustrate one embodiment of the invention,

Figure 1 is a front elevation of a machine embodying the invention.

Figure 2 is a side elevation, partly in section, of the machine shown in Fig. 1.

Figure 3 is a section on line 3—3 of Fig. 1.

Figure 4 is a detail hereinafter described.

The illustrated embodiment of the invention comprises a pair of co-acting feed rolls 10 and 11 arranged between a pair of spaced apart uprights 12, 12 fixedly mounted upon a base 13, said uprights and base forming the main frame of the machine. Also disposed between the uprights 12, 12 just below the feed rolls is a pair of bladed work-rolls 14 and 15 which are constructed and cooperate with one another as shown and described in my Patents Nos. 1,077,207 and 1,204,914 but which co-act with the feed rolls 10 and 11 in the novel fashion presently to be described.

The rear feed roll 10 is fast on a shaft 16 journaled in bearings on uprights 12, 12 and on one end of this shaft is fixed a finder gear 17 as shown in Fig. 2, while on the opposite end thereof are mounted three pulleys 18, 19 and 20 disposed side-by-side as shown in Fig. 1, the intermediate pulley 19 being fast on shaft 16 and the two end-most pulleys 18 and 20 being loosely mounted thereon. Co-operatively associated with pulleys 19 and 20 is a straight driving belt 21 and co-operatively associated with pulleys 18 and 19 is a crossed driving belt 22. The portions of these belts which engage the pulleys are continuously driven in opposite directions as indicated by the arrows in Fig. 1 and are spaced apart a distance slightly greater than the width of the intermediate pulley 19.

Slidably mounted in bearings provided at the tops of the uprights 12, 12 of the frame is a manually operated shipper member 23 in the form of a transversely disposed endwise movable slide-bar carrying a pair of laterally extending arms 24 which embrace a stretch of the belt 22 and also a pair of laterally extending arms 25 which embrace a stretch of the belt 21. It will thus be clear that the shipper member 23 can be adjusted endwise so as to place belt 21 on tight pulley 19 and belt 22 on loose pulley 18 to drive shaft 16 in one direction as shown in Fig. 1; so as to place belt 21 on

loose pulley 20 and belt 22 on loose pulley 18 to stop the rotation of shaft 16, or so as to place the belt 22 on tight pulley 19 and belt 21 on loose pulley 20 to drive shaft 16 in the opposite direction, all at the will of the operator. Stop pins 26 carried by the shipper member engage the uprights 12, 12 to limit the endwise movement of said member in each direction.

The rear work roll 14 is fixed on a shaft 27 supported, as usual, in journal boxes adjustably mounted on the uprights 12, 12. This shaft has fixed on it a pulley 28, Figs. 1 and 2, that is continuously driven in the direction of the arrow by a belt indicated by broken lines at 29.

The front work roll 15 is fast on a shaft 30 journaled near its opposite ends in bearings provided on a pair of swinging arms 31, 31, pivotally supported at their lower ends by a rock shaft 32 journaled in bearings on the uprights 12, 12. Each swinging arm 31 is connected by a pitman 33 with an eccentric 34 fast on a shaft 35.

The shaft 27 of the rear work roll has fast on it a gear 36 operating through the usual intermediate gears 37 to drive a gear 38 fast on the shaft 30 of the front work roll 15.

The shaft 35 has loosely mounted on it a gear 39 that is continuously driven by a pinion 40 fast on a shaft 41. This shaft 41 also has fixed on it a pulley 42 that is continuously driven by a belt, the latter being indicated by dotted lines at 43 in Fig. 1.

The front feed roll 11 is fast on a shaft 44 which is mounted as usual upon the upper ends of the swinging arms 31 and at one end thereof said shaft has fixed on it a finder gear 45 to co-operate with the finder gear 17 on the shaft 16 of the rear feed roll.

When the swinging feed roll frame or carrier comprising the arms 31 and rock shaft 32 occupies the full line position shown in the drawings the gears 17 and 45 are in mesh and if either belt 21 or 22 is on the tight pulley 19 the two feed rolls are rotated in unison, in the directions indicated by the arrows in Fig. 3 if belt 21 is on the tight pulley and in opposite directions if the belt 22 is on said pulley.

When the swinging frame or carrier 31—32 occupies the position indicated by broken lines in Fig. 3 the gear 45 is out of mesh with the gear 17 and therefore the front feed roll is at rest.

The two work rolls 14 and 15 are continuously driven in unison in opposite directions as indicated by the arrows in Fig. 3 and the peripheral speed of each is greater than that of the feed rolls 10 and 11.

55

As shown in Fig. 1, one face of the hub of the large gear 39 on the eccentric-carrying shaft 35 is constructed to co-operate as a clutch member with a supplemental clutch member 46 splined on shaft 35 and yieldingly urged toward the large gear 39 by a coiled spring 47 mounted on shaft 35 between said clutch member 46 and the adjacent upright 12.

As shown in Fig. 4, the clutch member 46 is made with two radial studs 48 and 49 to co-operate with a clutch-operating member 50 that is pivotally mounted at 51 on the adjacent upright 12. This member 50 is in the form of a bell-crank lever whereof one arm normally rests by gravity upon the clutch member 46 in the path of the studs 48 and 49 and is formed with a cam surface and stop shoulder to cooperate in the usual manner with said studs.

The other arm of the clutch operating member 50 is co-operatively associated with one arm of a bell-crank lever 52 fulcrumed at 53 on the adjacent upright 12. At its front free end the horizontal arm of the lever 52 is connected with one end of a horizontal cross-bar 54 whose opposite end is connected with the front free end of a horizontal arm 55 whose rear end is pivotally mounted at 56 on the other upright 12. The two pivots or fulcrums 56 and 53 are axially aligned. As will be clear, the lever 52, cross-bar 54 and arm 55 make up a foot-operated treadle through which the operator controls the clutch-operating member 50 and clutch member 46. A spring 57 normally holds this treadle elevated against the hubs of the swinging arms 31 but when depressed by the operator the treadle acts to swing member 50 out of engagement with clutch member 46 whereupon spring 47 shifts the latter into engagement with the clutch member on gear 39 with the result that said shaft is rotated and will continue to be rotated so long as the treadle is held down by the operator.

When the operator releases the treadle the latter is restored to its normal position by spring 57 which permits member 50 to fall on to clutch member 46 in front of an approaching stud 48 or 49. When the stud reaches the member 50 it rides against the cam portion thereof and the latter acts through the stud to disengage clutch member 46 from gear 39 thereby stopping the rotation of shaft 35 and eccentrics 34.

The studs 48 and 49 are positioned relatively to the eccentrics so that the swinging carrier 31-32 can be stopped and held either at the limit of its movement toward the rear work roll 14 or at the limit of its movement away from said roll and with the above described feed roll mechanism it is possible to introduce the skin, hide or leather into the machine while said carrier occupies either of said two extreme positions. Heretofore the feed rolls of machines of this swinging frame or carrier type have always been rotated only in the directions indicated by the arrows in Fig. 3 and no provision has ever been made for reversing their direction of rotation or for driving them in the opposite direction so as to feed the material into the machine. Nor has it been possible heretofore to introduce, operate upon and remove the skin, hide or leather while the swinging frame or carrier 31-32 occupied its closed position shown by full lines in Fig. 3.

Fixedly attached to the upper ends of the arms 31 is a table 58 upon which the skin, hide, leather or the like, X is placed, flattened out and slid forward to and between the feed rolls 10 and

11 while the carrier or swinging frame 31-32 occupies either its open or its closed position.

It will be clear that at any time during the operation of the machine the material X can be quickly released and the action of the rolls thereon terminated by depression of the treadle 52-54-56 which results in movement of carrier 31-32 from the full line position of Fig. 3 to the position indicated by dotted lines. Also, that a second depression of the treadle restores the carrier 31-32 to the full line position again.

Therefore, in operating the present machine to stake dry or semi-dry leather the latter may be fed into the machine to a predetermined or desired extent with the swinging frame on carrier 31-32 in closed position and then the removal of the leather may be effected by opening movement of said swinging frame. This mode of operation avoids the formation of wrinkles in the leather.

Directly below the work rolls 14 and 15, I provide a pair of stretching and tensioning rolls 57 and 58, the former having a covering 59 of resilient rubber and the latter being constructed with spiral metallic blades as shown in Figs. 1 and 3. Like the blades of the work roll 15 the blades of roll 58 are made in right and left hand directions as shown in Fig. 1, said right and left hand blades meeting at the vertical median plane of the machine.

The roll 57 is provided at its opposite ends with trunnions 60 journaled in bearings provided on the uprights 12 of the main frame while trunnions 60 provided at the opposite ends of the front roll 58 are journaled in bearings provided on the swinging arms 31.

These two rolls 57 and 58 are adapted to engage opposite sides of the skin, hide or leather X as the latter is moved up and down by the feed rolls 10 and 11 and while the work rolls 14 and 15 are operating upon the opposite sides of the same. It will thus be clear that the portion of the skin, hide or leather between the rolls 57 and 58 of the feed rolls 10-11 is maintained under longitudinal tension while being operated upon by the work rolls 14 and 15.

The front bladed roll 58 carries a sprocket wheel 61 connected by a sprocket chain 62 with a sprocket wheel 63 fast on the shaft 30 of the front work roll 15 so that said front roll 58 is continuously driven in the direction of the arrow, Fig. 3. The rear roll 57 is connected with and driven by the shaft 27 of the rear work roll 14 through similar mechanism including the sprocket chain 64 shown in Fig. 3. Thus the two lower rolls 57 and 58 are continuously driven in the directions indicated by the arrows in Fig. 3 and their peripheral speeds are no less, and preferably somewhat greater than, the peripheral speeds of the work rolls 14 and 15.

Thus during the operation of the machine the lower stretch of the skin, hide or leather between the work rolls 14-15 and the lower rolls 57-58 is maintained stretched taut longitudinally and also, through the action of the spiral blades of roll 58 said lower portion of the skin, hide or leather is stretched laterally in opposite directions from the middle of the machine. In this way the lower portion of the work is maintained perfectly flat and stretched in all directions at all times but particularly during the upward movement of the work while said lower portion of the latter is approaching and passing between the work rolls 14 and 15.

The above described machine is of simple and

efficient construction and has the advantage that it not only can be operated as machines of this class have heretofore been used but may be controlled so as to have the new mode of operation above described.

For example:—In staking more or less dry leather the latter can be placed between the feed rolls while the latter are open and then, after closing the feed rolls by means of foot treadle 10 52—54, the leather will be fed downwardly half-way whereupon, by operation of the foot treadle, the feed rolls can be opened to permit the leather to be manually restored to the table and reversed for treatment of its other half.

15. In putting out wet skins the leather or hide is introduced between the rolls while the swinging frame or carrier occupies its open position, and then after closing the frame or carrier the leather is fed downwardly as far as possible by 20 the feed rolls whereupon the direction of rotation of the feed rolls is reversed to bring the leather or hide back up again and the foot treadle is then operated to open the feed rolls and free the same.

25. What I claim is:

1. In a machine of the character described, the combination of a pair of opposed spirally bladed work rolls for simultaneously engaging the opposite sides of the sheet material that is operated upon; means for continuously rotating said rolls to cause the same to scrape said material and also to stretch the same longitudinally and transversely; a pair of opposed feed rolls disposed above and adjacent to said work rolls so as to co-act with the latter in stretching the material longitudinally; a main frame on which one roll of each of said two pairs is journaled; a swinging carrier frame pivotally supported by said main frame and on which the other rolls of said two pairs or rolls are rotatably mounted; mechanism for driving said feed rolls to feed the material into the machine toward and between said work rolls at a slower speed than the peripheral speed of said work rolls, and mechanism for swinging said carrier frame in a direction to release the material from both pairs of rolls when said material has been fed into the machine a predetermined distance.

2. In a machine of the character described, the combination of a pair of opposed spirally bladed work rolls for simultaneously engaging the opposite sides of the sheet material that is operated upon; means for continuously rotating said rolls to cause the same to scrape said material and also to stretch the same longitudinally and transversely; a pair of opposed feed rolls disposed above and adjacent to said work rolls so as to coact with the latter in stretching the material longitudinally; mechanism for driving said feed rolls to effect movement of the material toward and between said work rolls; mechanism for driving said feed rolls to effect movement of the material between said work rolls in the opposite direction; means for selectively controlling said two driving mechanisms to render either effective to the exclusion of the other; a stationary main frame on which one roll of each of said two pairs of rolls is journaled; a swinging carrier frame pivotally supported by said main frame and on which the other rolls of said two pairs of rolls are rotatably mounted; manually controlled means for swinging said carrier frame to shift the rolls carried thereby into and out of cooperative relationship with the other rolls of the machine and

for holding said swinging carrier stationary while at the limit of its movement in each direction.

3. In a machine of the character described the combination of a pair of opposed bladed work rolls for simultaneously engaging the opposite sides of the sheet material that is operated upon; means for continuously rotating said rolls to cause the same to scrape said material and also to stretch the same longitudinally and transversely; a pair of opposed feed rolls disposed above and adjacent to said work rolls so as to co-act with the latter in stretching the material longitudinally; mechanism for driving said feed rolls to effect movement of the material toward and between said work rolls; mechanism for driving said feed rolls to effect movement of the material between said work rolls in the opposite direction; means for selectively controlling said two driving mechanisms to render either effective to the exclusion of the other; a pair of opposed tensioning rolls disposed below said work rolls so as to engage the opposite sides of that portion of the sheet material extending below the latter, and means for rotating said tensioning rolls in directions opposed to the upward movement of the sheet material.

4. A machine of the character described constructed in accordance with claim 3 and wherein there is provided a main frame on which one roll of each of said three pairs of rolls is journaled; a swinging support for the other rolls of said three pairs; manually controlled means for swinging said support to shift the rolls carried thereby into and out of co-operative relationship with the other rolls of the machine, and for holding said support at the limit of its movement in each direction.

5. A machine of the character described constructed in accordance with claim 3 wherein one of said tensioning rolls is made with right hand and left hand spiral blades to co-operate with the opposite tensioning roll to stretch the sheet material laterally in opposite directions from its middle.

6. A machine of the character described constructed in accordance with claim 3 and wherein a swinging support is provided for one of said feed rolls, one of said work rolls and one of said tensioning rolls, and including also manually controlled means for swinging said support back and forth to shift the rolls carried thereby into and out of co-operative relationship with the other rolls of the machine, one of said tensioning rolls having a resilient surface for engaging one side of the material and the other of said tensioning rolls being made with opposed spiral blades for stretching the material laterally in opposite directions from its middle.

7. In a machine of the character described the combination with a pair of opposed bladed work rolls for simultaneously engaging the opposite sides of the sheet material that is operated upon and means for continuously rotating said rolls to cause the same to scrape said material and also to stretch the same longitudinally and transversely, of a pair of opposed feed rolls disposed above and adjacent to said work rolls so as to co-act with the latter in stretching the material longitudinally; mechanism for driving one of said feed rolls to effect movement of the material between said work rolls in one direction; mechanism for driving one of said feed rolls to effect movement of the material between said work rolls in the opposite direction; means for selectively controlling said two driving mecha-

nisms to render either effective to the exclusion of the other; a pair of tensioning rolls disposed below said work rolls; means for continuously rotating said tensioning rolls; a swinging frame on which one of said feed rolls, one of said work rolls and one of said tensioning rolls are mounted, and means controlled by the operator for shifting said swinging support to move the three

rolls carried thereby into and out of operative positions, one of said tensioning rolls being made with opposed spiral blades for stretching the material laterally in opposite directions from its middle as said material is moved up and down between said work rolls. 5

FRANK WAYLAND.
